Primary Examiner — Rosemary K Tarcza*Assistant Examiner* — Sanjeev Paul(74) *Attorney, Agent, or Firm* — Dunlap Bennett & Ludwig PLLC(57) **CLAIM**

The ornamental design for a pillow, as shown and described.

DESCRIPTION

FIG. 1 is a perspective view of a pillow, shown in use;
 FIG. 2 is a perspective view thereof;
 FIG. 3 is a front elevation view thereof;
 FIG. 4 is a rear elevation view thereof;
 FIG. 5 is a left elevation view thereof, illustrating the pocket open;
 FIG. 6 is a left elevation view thereof;
 FIG. 7 is a right elevation view thereof; and,
 FIG. 8 is a top plan view thereof, the bottom plan view being a mirror image thereof.
 The broken lines shown in the drawings illustrate portions of the pillow that form no part of the claimed design.

1 Claim, 3 Drawing Sheets(56)
